UNITED STATES PATENT OFFICE.

MARY MATTHEWMAN, OF LONDON, ENGLAND.

ADVERTISING DEVICE.

Application filed January 17, 1924. Serial No. 686,848.

To all whom it may concern:

Be it known that I, MARY MATTHEWMAN, a subject of the King of Great Britain, residing in London, England, have invented 5 certain new and useful Improvements in Advertising Devices, of which the following is a specification.

This invention has for its object an improved advertising apparatus of the kind 10 wherein a band, chain or similar flexible member moves over suitably arranged sprocket wheels and carries detachably supported interchangeable designs, letterings, figures, models or other symbols or elements for advertising purposes, which symbols are intermittently exhibited before a window or panel in the casing of the apparatus, the symbols being supported on the moving band or similar flexible member 15 to form a horizontal row and independently one of another so that any one of the symbols can be detached or changed without displacement of an adjacent symbol, and wherein lighting means, such as electric 20 bulbs, are preferably provided in order that a displayed advertisement may be made visible and attractive at night in addition to being visible by day without the use of the illuminating means.

30 In the improved apparatus the symbol-supporting member is arranged to travel within the casing in a horizontal or a substantially horizontal direction, so that symbols assembled lengthwise of the flexible 35 supporting member and thereby forming a horizontal row, come singly into view through the window or panel and follow one another past said window or panel.

Moreover, each of the symbols forming 40 a row is independently mounted on the supporting member and is preferably attached thereto in such a way that it cannot of itself move bodily in any direction relatively to the said member or be displaced bodily 45 without the symbol being bent or flexed.

The invention will be further described with reference to the accompanying drawing, in which:—

Fig. 1 is a sectional plan of a portion of 50 the casing of one form of the apparatus, constructed according to the invention, the advertising symbols being detachably mounted on the endless moving band.

Fig. 2 is an elevation of a portion of the 55 endless band shown in Fig. 1.

Fig. 3 is a fragmentary elevation of a portion of a modified form of the endless band, and Fig. 4 is a sectional plan of the band shown in Fig. 3.

In the several figures corresponding parts 60 are denoted by the same reference numerals.

The casing 1 of the improved apparatus may be of any convenient construction and design, and is provided with a front opening 2 in which is fitted a sheet 3 of glass 65 or other transparent material. Within the casing is mounted a band 4 that travels horizontally over a plurality of rollers or guides 6, a pair of which is shown in Fig. 1, and advertising symbols are detachably 70 mounted on the band in such a way that, as the band travels round the rollers, the symbols will come into view through the opening 2, and pass out of view, one after another. 75

A convenient way of mounting the symbols is to form a number of slits or slots 9 in an endless band 10, and to provide each advertising element or symbol 11 with fingers or lugs 12. The lugs 12, which are 80 formed integrally with the body portions of the symbols 11 and lie in substantially the same planes as such body portions, are located at or adjacent the leading edges of the symbols, as shown in Figs. 2 and 3, and the slots 9 in the band are spaced apart at a distance one from another which is preferably less than the width of the symbols, as shown in Figs. 1 and 2. In consequence of such arrangement of the lugs 85 and slots, the leading edge of each symbol will be overlapped by the trailing edge portion of the next preceding symbol so that none of the leading edges of the symbols are exposed. In this way risk that symbols 90 moving in one direction along one path may engage with symbols moving in a reverse direction along an adjacent path—for example where the flexible supporting member or band is mounted to move in a zig-zag path or in a path forming a closed loop—is avoided. The elements 11 are each applied to one face of the band 10, and the fingers 12 thereon are pushed through and 95 engage in the slots 9, as indicated in Figs. 1—4. In such arrangement the elements 11 may be of either flexible or rigid material. The band carrying the elements 11 so mounted is arranged to travel generally in the direction of the arrow in Fig. 1, the edges 100

105 engage in the slots 9, as indicated in Figs. 1—4. In such arrangement the elements 11 may be of either flexible or rigid material. The band carrying the elements 11 so mounted is arranged to travel generally in the direction of the arrow in Fig. 1, the edges 110

of the elements provided with the fingers 12 being the leading edges.

By mounting the symbols in either of the above ways, any one of them can be removed 5 or replaced without displacing any of the adjacent symbols.

In the arrangement shown in Figs. 1 and 2, the band is of transparent or semi-transparent material, and the elements 11 may 10 be either of a like material, a part of each element being rendered non-transparent or opaque by any suitable means, or of an opaque material with the advertising letters or device cut or stencilled out.

15 In the arrangement shown in Figs. 3 and 4, the endless band 13 is of non-transparent material and is provided with a series of openings 14 along its length of any desired configuration. The advertising 20 elements or symbols 15 are of a transparent or translucent substance and comprise a symbol portion and a ground portion, one or other of such portions being rendered opaque according to whether the 25 ground of the symbol is to be transparent or translucent in front of the openings 14.

Having thus described the nature of the said invention and the best means I know

of carrying the same into practical effect, I claim:—

1. Advertising apparatus of the character described, comprising a casing, a plurality of rollers mounted within the casing, an upright movable flexible band extending around portions of the rollers, said band 30 having a longitudinally-extending row of slots adjacent each of its opposite edges, and a plurality of juxtaposed flexible advertising symbols each having an integrally formed substantially co-planar lug projecting from its upper edge for engagement with a slot of the row of slots adjacent the upper edge of said band and a similar lug projecting from its lower edge for engagement with a slot of the row of slots 35 adjacent the lower edge of said band, each of said lugs being adjacent a side edge of the symbol with which it is associated.

2. Advertising apparatus according to claim 1, wherein each advertising symbol 40 overlaps the leading edge of the immediately following advertising symbol.

In testimony whereof I have signed my name to this specification.

MARY MATTHEWMAN.
